VENDING MACHINE

Paul L. Geer, Berkeley, Calif.

Application June 24, 1936, Serial No. 86,997

8 Claims. (Cl. 194—39)

The invention relates to a coin-controlled vending machine.

An object of the invention is to provide a generally improved apparatus for the selective vending of articles therefrom.

A more specific object is to provide an improved vending machine such that articles of different value may be selectively vended therefrom following the deposit of an appropriate coin or coins.

10 Another object is to provide an improved coin-controlled means wherein a common assembly controls the vending of all of the articles at the different prices.

15 Another object is to provide means whereby the delivery movement of an ejector element to deliver a package must be completed before the ejector element may be returned to its initial position.

20 Another object is to provide for the automatic return to the operator of an improper object which may have been deposited in the apparatus in lieu of a proper coin.

25 Yet another object is to provide for the automatic weighed-out discharge from a coin-guiding rollway leading to the coin-controlled mechanism of a slug deposited therein.

30 The invention possesses other objects and features of advantage, some of which, with the foregoing, will be set forth or be apparent in the following description of a typical embodiment of the invention, and in the accompanying drawings, in which,

35 Figure 1 is a perspective exterior view of a vending machine unit embodying the present invention.

Figure 2 is an enlarged section at 2—2 in Figure 1.

40 Figures 3 to 5 inclusive are enlarged fragmentary views showing an article-ejecting member of the apparatus in initial and intermediate and limiting positions respectively.

Figure 6 is a fragmentary section at 6—6 in Figure 3.

45 Figure 7 is a fragmentary front elevation, an upper front casing member and a magazine assembly being removed.

Figure 8 is an elevation at 8—8 in Figure 7.

50 Figure 9 is an enlarged front view of a coin-releasing and directing element and its mounting, the view being taken generally at 9—9 in Figure 8.

Figure 10 shows the members which make up the assembly of Figure 9, separately and in transversely separated relation.

55 Figure 11 is a section at 10—10 in Figure 9.

Figure 12 is a stepped plan view and section of the apparatus.

Figure 13 is a fragmentary section at the line 13—13 in Figure 12.

5 Figures 14 to 16 inclusive are generally diagrammatic views indicating the selective freeing of an article ejecting member in accordance with the amount of money deposited by the purchaser.

Figure 17 is a fragmentary section at 17—17 in Figure 13.

10 The features of present invention are shown as being embodied in the structure of a unitary vending machine which is arranged for the vending of rectangular articles or packages 21 from a plurality of stacks of the articles which are 15 provided in a series of upright spaces 22 of a supply magazine. As is particularly brought out in Figures 3 to 6, 12 and 13, the magazine spaces 22 are provided in a unitary structure 20 which may be formed of sheet metal and essentially 20 comprises a closed back wall 23, end walls 24, and partitions 25 dividing the space between the walls 24 to provide the line of magazine spaces. Mutually coplanar flanges 26 are provided at the front edges of the walls 24 and partitions 25 25 whereby to prevent a forward movement of the articles from the magazine spaces while providing openings for viewing the packages.

30 Flanges 27 are provided at the bottoms of the walls 24 and partitions 25 whereby they define partial bottoms for the magazine spaces and may support the stacks of articles therein against a downward escape of the bottom article. The rear wall 23 terminates at a distance above the plane of the flanges 27 which exceeds the thickness of 35 a package 21 and is less than twice the thickness of the package. In this manner, when a stack of articles is supported on the flanges 27 at the bottom of a magazine space 22, the bottom article 40 of the stack may be pushed rearwardly from below the stack to fall upon a sloping and fixed apron 28 for sliding delivery to the purchaser; the apron 28 comprises the bottom of a delivery chute or passage which is common for all of the 45 magazines. The flanges 27 for each magazine are mutually coplanar, as is shown.

50 Means are provided for effecting the described delivery of an article 21 from a selected stack, said means comprising movable ejector elements 29 which are independently operative at the bottoms of the magazine spaces 22. Normally, each ejector 29 supports a stack of the articles on a flat top face thereof which lies in a plane which is parallel to the plane of the support flanges 27 55

and is no more than the thickness of a package 21 above the latter plane.

The ejectors 29 are mounted for rectilinear reciprocation to and from their normal positions 5 below the stacks whereby an ejector 29 may be pulled forwardly to permit a dropping of the stack therefrom upon the flanges 27 of the magazine thereat, after which a rear end portion of the ejector below its top 31 may push the bottom 10 package rearwardly from beneath the stack and onto the apron 28 while the ejector reassumes its supporting position with respect to the remaining articles in the stack.

As is particularly brought out in Figures 3 and 15 4 and 5 and 12 and 13, the ejectors 29 are mounted on and above a horizontal plate 32. Mutually 20 parallel ribs 33 extend upwardly from the plate 32 in the plane of the end walls 24 and partitions 25 of the described magazine unit 20, and said 25 unit is supported on the tops of the ribs 33 which engage beneath the flanges 27. Slideway grooves 34 are provided in the mutually opposed faces of the ribs 33 for slidably receiving the free side edges of flanges 35 which extend laterally from 30 the bottoms of the members 29. It will be noted that the portions of the members 29 above the flanges 35 thereof are narrower than the slots defined between the support flanges 27 whereby their upper surfaces may be disposed within the magazine spaces as described.

Pull rods 36 extend forwardly from the members 29 to protrude from the casing of the vending machine whereby the members 29 may be selectively pulled forward for the deposit of a package 35 21 behind the member and for its subsequent ejection. The under side of one flange 35 is formed with ratchet teeth 37 of rectangular cross-section, and a free-swinging pawl 38 is pivotally supported on the plate 32 and beneath the flange 40 35 for such engagement with the teeth 37 that a movement of the ejector in either a forward or return direction must be completed before a movement in the reverse direction may be effected.

As illustrated in Figures 3 to 6 inclusive, the 45 pawl 38 is intermediately pivoted, is normally disposed in a vertical position, and has its center of gravity below its pivot point whereby it tends to gravitationally retain its vertical position. When an ejector 29 is disposed in its rearward 50 position, the top portion of the pawl 38 which may 55 coact therewith and is wider than the spaces between the ratchet teeth is disposed forwardly of the line of ratchet teeth, as is shown in Figure 3. When the member 29 is pulled forwardly the 60 movement of the ratchet teeth over the pawl engages the top of the pawl to rock this pawl portion forwardly whereby a recessive movement of the member is prevented, this being illustrated in Figure 4. When the full forward stroke of the 65 member 29 is made, the pawl is disposed rearwardly of the line of ratchet teeth whereby it may again swing clear and to its normal upright position. Upon a return movement of the member 29, the pawl 38 is again operative to limit the member 70 to a one-way movement, but oppositely from its operation while the member is being pulled forwardly. The described operation of the pawl 38 is understood to insure the completion of a package-ejecting cycle of movements of a member 29 when the actuation thereof has been appreciably started.

Means are provided to automatically bar access to the bottom package of a stack of packages when an ejector 29 therefor is moved forwardly.

75 As illustrated in Figures 2 and 7 and 12, a swing-

ing apron 39 is mounted behind the magazine assembly for swinging about a horizontal axis above the magazine bottom and for disposing the lower apron portion between the lower package of the stack which rests on the flanges 27, and the fixed delivery apron 28. A rock-shaft 41 is mounted on and beneath the plate 32 forwardly thereon, and radial arms 42 of the shaft extend upwardly through slots in the plate and into the paths of movements of the members 29 in such a manner that a forwardly disposed member 29 will engage an arm 42 to rock the shaft 41.

At an end of the shaft 41 beyond the magazine assembly an arm 43 extends upwardly, as is brought out in Figure 2, and the free end of said arm is connected to a lower point of the apron 39 by means of a link 44; in this manner, the access of a hand through the forwardly-opening article-discharging passage defined between the apron 28 and the plate 32 to a lowered package in a magazine is automatically prevented by disposing the apron 39 below the discharge point from the magazine before the stack therein may be lowered by reason of the removal of the member 29 from beneath it. A tension spring 40 is constantly 25 operative between the link 44 and a fixed anchorage to constantly urge an inoperative disposal of the apron, it being noted that the spring 40 is operative while an arm 43 is engaged and rocked by an ejector 29 to urge a return movement of the 30 ejector.

It will now be noted that the present vending machine is particularly arranged for the vending of articles which may sell at different prices; by way of illustration, it will be assumed that the 35 prices may be five cents and ten cents and fifteen cents for articles in different stacks of the magazine. Furthermore, means are provided whereby, following the deposit of an appropriate coin or coins, only a single package of no greater value 40 than that paid for may be obtained from the machine by the purchaser who is to operate the machine for himself.

An upwardly offset portion 45 of the support plate 32 extends for the length of the plate in 45 intersecting relation to the ribs 33 and defines therein a downwardly opening and elongated groove 46 of uniform cross-section. A plate member 47 is fixed along and beneath the bottom of the plate 32 to laterally close the groove 46 thereat. The closed and elongated space thus defined within the offset plate portion 45 is arranged to contain a series of normally contacting members for limited separation in their line. The latter members include a member 49, balls 49, members 50, and a member 51. The member 48 is shown as fixed within the groove space 46 at what is shown as the left end thereof, and contacts a ball 49 in the groove. The members 50 are preferably cylindrical and have ends rounded with the same 60 curvature as the balls 49.

The member 51 engages and extends beyond the ball 49 at the right end of the line of members in the groove 46 and is provided with a radial arm 53 which extends downwardly through a slot 54 in the plate 47. A tension spring 55 extends from the free end of the arm 53 to an anchorage 56 on the plate 47 and to the left of the slot 54 whereby to yieldingly maintain a contacting relation of the line of members 49 and 50 between the members 47 and 51. It will be noted that the members 50 are each the operative equivalent of a ball member 49 in the line and may be either replaced with balls 49 or may replace some of the balls as may be desired or required for effecting the exact 75

positioning of contact points of the members for a purpose which is hereinafter brought out.

Plates 57 depend from the bottoms of the ejector members 29, said plates extending for the 5 lengths of the members and being of uniform thickness except that their forward ends are bevelled to provide wedge points thereat; these members are hereinafter referred to as wedge plates. The offset 45 of the support plate 32 is provided 10 with transverse slots or cuts 59 in the planes of movement of the wedge plates 57 for freely receiving the wedge plates therethrough. The balls 49 and/or members 50 are mutually tangent in the planes of movement of the wedge points 15 whereby, with the conditions as in Figure 3, the forward movement of a given ejector 29 will engage the wedge plate 57 thereof between members in the groove to separate the same thereat and permit the passage of the wedge plate 20 through the line of members, unless such operation is prevented. It will be understood that when a spreading of the members 49 and 50 in their line is prevented, the assembly of said members is unitarily operative as a stop means with 25 respect to the various ejectors 29.

Means are provided for preventing the passage of the wedge plates 57 through the line of members 49 and 50, and an operative movement of the ejector, unless an appropriate coin or token has 30 been deposited in the machine. To this end, a notch 60 is provided in the upper side of the member 51, said notch registering with a like notch 61 in the top of the offset 45. Stop or 35 detent elements 62 and 63 normally extend downwardly through the notches 60 and 61 whereby the member 51 is locked against its displacement by the operation of a wedge plate 57 at a slot 59 to urge a pushing back of the member 51. The 40 detents 62 and 63, it will be noted, are of different thicknesses, and the different wedge plates 57 have the thickness of one of these detents 62 or 45 63, or their sum in accordance with the value of articles to be discharged by the ejectors which carry them. The wedge plates 57 may be removably and replaceably mounted on the ejectors, as by screws 58 shown in Figure 6, whereby a given ejector may be readily adapted for the vending of articles of different values.

If the detent 62 is lifted out of the notch 60, as 50 is shown in Figure 14, a wedge plate 57 of the same thickness as the detent 62 may separate the line of members 49 and 50 to permit a forward and operative movement of the ejector which carries that wedge plate, the detent 63 being 55 transversely deflectable to permit this. If the detent 63 is removed, as in Figure 15, one wedge plate which has the thickness of the detent 63 may extend through the line of members to permit the ejection of a package. If both of the 60 detents 62 and 63 are displaced from their normal operative relation to the member 51, the ejector member carrying a wedge plate 57 having the combined thicknesses of the detents may be operated.

65 It will now be noted that the detent 62 is arranged to be rendered inoperative by and upon the deposit of a five cent piece, or nickel, in the machine, and the detent 63 may be displaced by or upon the deposit of a ten cent piece, or dime, in the machine. Under these conditions, and in terms of the showing of Figures 14 to 16, the deposit of a nickel in the machine will release solely the right-hand ejector 29 for its operative actuation, the deposit of a dime in the machine will 70 release the next ejector in the line, and the de-

posit of both coins will release the third and fourth ejectors in the line. In this manner, the different magazines for the different ejectors may contain packages of sale values which correspond to the deposit of coin required for their purchase. 5

It will be understood that only the thinnest wedge plate 57 may be pulled through the line of members 49 and 50 when only the detent 62 is displaced. When the detent 63 is displaced, as in Figure 15, either a five cent or ten cent package 10 may be obtained from the machine by operating an appropriate ejector. And when both detents are removed, a fifteen cent article may be obtained. The engagement of the pin 53 of the member 51 with the right end of the slot 54 is 15 provided for as a means to limit the spreading of the members 49 and 50 to that required for vending but one fifteen cent article, whereby but one article may be obtained with a deposit of fifteen cents. 20

The coin control for the detents 62 and 63 is mounted on an upright plate 64 which is disposed opposite the right end of the magazine assembly. Zig-zag rollways or chutes 65 and 66 are defined at opposite faces of the plate 64 and terminate 25 at a normally operative and displaceable stop element 67 at the bottom of the rollways. Similar levers 68 are intermediately pivoted on the plate 64 for rocking in planes parallel to that of the plate and each have one arm portion 69 disposed in the rollways 65 and 66 adjacent the stop member. The other arms 71 of the levers 68 pivotally carry the stop members 62 and 63, said stop members being suitably guided in upright position and being arranged to be gravitationally 30 retained in operative disposition in the notch 60 unless a coin in a rollway 65 or 66 is supported and retained on their arms 69. 35

It will now be noted that the stop member 67 provides portions which are normally disposed in the plane of a coin supported on a lever arm 69 in a rollway 65 or 66, and provides coin discharge passages therethrough for selective registration with a coin to be released. With respect to each rollway, one of said passages connects with a coin chute 72 which discharges upon the apron 28 for the return of the released coin. The other passage discharges a coin downwardly into a bottom portion of the machine casing for removal by an authorized person, said casing portion comprising 40 a coin box. 45

By reference to Figures 2 and 8 to 11, it will be noted that the member 67 is in the general form of a rectangular block, is supported on a plurality of spring arms 73 fixed to the plate 64 and normally disposing it in operative relation to the rollways, and has its central plane normally disposed in the central plane of the plate 64, said plate being notched out to receive the member 67. The assembly of the element 67 comprises a central member 74, outside members 75 and 76, and intermediate members 77 and 78 which are disposed between the member 74 and the members 75 and 76 respectively. The various members at 55 either side of the central member 74 cooperate to provide rearwardly directed coin passages 79 which connect with the coin chute 72, and are also cooperative to provide downwardly directed passages 80 through which coins may pass to the coin box portion of the casing. 60

It will now be noted that the spring arms 73 normally dispose the element 67 with the front edges of the members 77 and 78 thereof operative as a stop against a coin in the bottom of a rollway 65 or 66, and that the spring support of 75

said element permits its transverse shifting to register either a passage 79 or a passage 80 with a coin in a rollway for a directed release of the coin. At the end thereof adjacent the plate 64, the swinging apron 39 carries an arm 82 for a wedging engagement with the element 76 of the stop member 67 to laterally displace the member and release a coin in the rollway 65 or 66 through a passage 80 when the apron is moved forwardly by reason of an operative forward movement of an ejector 29. In this manner, the deposited money is released for its retention in the coin box after the released ejector has been displaced to dispose its wedge plate through the line of stop members 49 and 50.

Referring now to the rollway 65 and 66 which a deposited coin must traverse for its disposal against the members 77 or 78 of the stop element 67, it is noted that the rollways are defined by suitably positioned ribs 83 which extend transversely from the plate 64. Plates 84 are mounted against the edges of the ribs 83 to define the outer rollway sides. The upper portion of the coin return chute 72 is branched to have portions 35 thereof disposed outwardly of the plates 84.

At the upper ends thereof, the bottoms and outer sides of the rollways 65 and 66 are defined by swinging flap-like members 86 which normally rest against the central plate 64, said members being arranged for outward displacement to release pieces of paper or other non-rolling objects which may be inserted in the rollway. The flaps 86 are positioned adjacent the front edge of the plate 64 and depend from horizontal hinge pins. A rod or bar 87 is mounted in upright position adjacent the front of the plate 64 and carries a wedge-like head 88 for wedged engagement with and between the flaps 86 to swing the same outwardly, the rod being normally disposed in a depressed and inoperative position.

A slide bar 89 is mounted in horizontal disposition on or adjacent the bottom of the plate 64 for rectilinear reciprocation, said bar extending forwardly from the machine casing for its manual manipulation and being normally disposed in a withdrawn position thereof through the operation of a tension spring 90. A wedge cam 91 is carried on the bar 89 for wedging engagement beneath the bottom end of the rod 87 for lifting the bar to displace the flaps 86 when the bar 89 is pulled forwardly; as shown, the bar 89 is slidably mounted on a plate 92 which supports an end of the plate 32.

At its rearward end, the bar 89 is provided with a wedge cam 93 extending transversely therefrom and arranged to engage the swinging stop 67 at its member 75 for displacing the stop to register the passages 79 thereof with the different rollways 65 and 66 when the bar is pulled forwardly. It will thus be understood that the pulling forward of the bar 89 is arranged to effect the return of a deposited coin upon the delivery apron 28 should a customer wish the return of a coin for which the goods have for any reason not been delivered.

Means are provided whereby the bar 89 is automatically retained against displacement when an ejector is operatively displaced, and vice versa. Accordingly, the bar 89 extends through a slot 45 across the offset 45 and is disposed just beyond the free end of the movable member 51 when the latter is in its normal position. As is brought out in Figures 12 to 17 inclusive, a notch or opening 94 is provided in the bar 89 for receiving the member 51 therethrough when the bar is in its

normal retracted position and the member 51 is displaced through the actuation of an ejector 29; under the latter conditions, the ends of the notch 94 engage the opposite sides of the member 51 to prevent an operative displacement of the bar 89. On the other hand, if the bar 89 is displaced from its normal position, it acts as a stop to prevent a displacement of the member 51 and therefore prevents a working displacement of an ejector 29 until it is restored to its normal position, as in Figure 17.

Means are provided in association with the rollways 65 and 66 for returning therefrom rollable articles which are not appropriate coins or tokens for use in the machine. Magnets 95 are mounted at upper points of the plate 64 with their poles transversely opposite the rollway portion thereat. If an iron slug or the like moves through the rollway, it is arranged to be retarded in its rolling motion by the action of a magnet 95 whereby it may fall through an opening in the rollway bottom which a non-ferrous article would normally jump and enter a branch 85 of the return duct 72 for its gravity discharge upon the delivery apron 28.

At intermediate points of the rollways 65 and 66, means are provided for rejecting and returning coins or other rollable discrete articles which are not of the requisite weight. Accordingly, a portion of the rollway bottom is provided with an opening which is closed by an arm 96 of a lever 97 having its other arms 98 counter-weighted in such manner that the arm 98 is normally held against an overlying stop 99 with such a degree of pressure that only a coin of normal, or greater than normal weight passing over the arm will depress the arm and fall through the opening thereat to continue toward the stop member 67. A coin or other object which is too light to depress the arm 96 will continue in a rollway portion which discharges into the return chute 72. In practice it has been found that the arm 96 should preferably comprise a length of relatively thin spring metal; the use of such an arm provides a more dependable separation of lighter and heavier coins. The present device provides a weighing selection of coins in a rollway, and it will be understood that a similar arrangement might be provided for weighing out coins or other objects which are heavier than proper for retention in a chute which leads to the stop member 67; in the latter case, the coin which displaces the arm 96 would be diverted and discarded.

The mechanism now described is arranged to be housed in a suitable casing having end walls 101, a back wall 102, a top 103, a bottom 104, and a stepped front wall 105. Sight openings 106 are provided in the upper portion of the front wall 105 opposite the magazine spaces whereby the packages in the magazine may be seen by a prospective customer. Coin-receiving openings 107 and 108 are provided in the front wall 105 in registration with the front ends of the rollways 65 and 66 respectively. The casing may be suitably opened for the removal of coins from the coin box and for access to its parts.

From the foregoing description taken in connection with the accompanying drawings, the advantages of the construction and the method of operation will be readily understood by those skilled in the art to which the present invention appertains. While I have described the features and the uses of an arrangement which I now consider to be a preferred embodiment of my in-

vention, I desire to have it understood that the showing is primarily illustrative, and that such changes may be made as fall within the scope of the following claims.

5. I claim:

1. In a coin-controlled machine for vending articles of different sale values from a line of mutually independent stacks thereof, movable ejectors arranged for independent operation at the different stacks and carrying wedge plates, a line of normally engaged members extending across the paths of movement of the wedge plates and contacting in planes including the wedge plates whereby the latter may be operative between contacting members to separate the same in their line when an ejector is displaced from its normal position, stop elements jointly coactive with the line of said members to prevent their separation and independently disposable in inoperative position to then permit different distances of separation of engaged members by a wedge plate operative between them, said wedge plates being of different thicknesses corresponding to the different distances of separation permitted for the members when the different stop elements are inoperative whereby only those ejectors may be actuated which have wedge plates of a thickness which is no greater than the distance of permitted separation of the members, and means utilizing a coin deposited in the machine to inoperatively dispose a stop element to thereby permit the operation of an ejector to free an article of corresponding value from a stack.

2. In a coin-controlled machine for vending articles of different sale values from a line of magazines therefor, movable ejectors arranged for independent operation at the different magazines and carrying wedge plates for displacement with the ejectors and in their planes, a line of normally engaged members extending across the paths of movement of the wedge plates and contacting in the planes of the wedge plates whereby a wedge plate may be operative between contacting members to separate the same in their line and permit a passage of the wedge plate through the line when the ejector carrying the wedge plate is operatively displaced from its normal position, a member at one end of the line thereof being fixed against movement and a member at the other end of the line being provided with a detent-receiving opening, a plurality of detents normally engaged in said opening and cooperative to prevent a separation of the members in the line thereof when a wedge plate is directed against the line of members, said detents being of different thicknesses in the direction of the line of members and wedge plates of different ejectors being of corresponding thicknesses whereby the inoperative disposal of a detent is arranged to permit the operative actuation of an ejector carrying a wedge plate of the same thickness as the removed detent, and means whereby a coin deposited in the machine is operative to effect the inoperative disposal of an appropriate detent to permit the actuation of an ejector for articles having the sale value of the deposited coin.

3. In a coin-controlled machine for the vending of articles from a magazine thereof, means normally operative to prevent an operative actuation of the ejector, means defining a coin-receiving chute, a displaceable stop member normally operative at the discharge end of the chute to engage a coin in the chute and providing an extension of the chute passage and mounted for its displacement to align its passage with the chute,

means operated by a coin being held by the stop member to render the first means inoperative for releasing the ejector, and means whereby the actuation of the released ejector is automatically operative to displace the stop member for aligning its passage with the coin to release the latter therethrough.

4. In a coin-controlled machine for vending articles from a magazine therefor, an ejector for actuation to discharge an article from the magazine, means normally operative to prevent an operative actuation of the ejector, means defining a coin-receiving chute, means defining a coin-returning passage, a displaceable stop member normally operative at the discharge end of the chute to engage a coin in the chute, means whereby a coin in the chute and engaging the stop member is operative to free the ejector for its operation, means whereby the actuation of the released ejector is operative to displace the stop member in a given direction for releasing the coin for its gravity discharge from the chute and for its retention in the machine, and a member independently operative against the stop member to displace it in an opposite direction for releasing the coin for its gravity discharge into the coin-returning passage.

5. A structure in accordance with claim 4 wherein a coin box is defined beneath the stop member and the stop member comprises an element providing means to appropriately guide a released coin from the coin-receiving chute to the return chute or to the coin box when the member is correspondingly displaced to release the coin.

6. A structure in accordance with claim 4 having means whereby the actuation of a freed ejector is automatically operative to prevent a simultaneous actuation of the coin-releasing member, and vice versa.

7. In a coin-controlled mechanism for vending articles from a magazine therefor, an ejector for actuation to discharge an article from the magazine, a displaceable stop member normally operative to prevent an operative actuation of the ejector, means defining a coin-receiving chute, a displaceable stop member normally operative to engage a coin in the chute to retain the coin in fixed position in the chute, means whereby a coin in the chute engaging the coin stop member is operative to release the first stop member to permit an operative actuation of the ejector, means defining a coin box in the machine, a member arranged for movement against the coin stop to displace the same in a given direction transverse to the chute at the coin for releasing the coin for its directed discharge into the coin box when the ejector is operatively actuated, means defining a coin-return passage for the machine, a member independently movable against the coin stop member to displace it in an opposite direction for releasing the coin for its directed discharge into the coin-return passage, and means whereby the ejector stop and the last member are directly engageable with each other to prevent the displacement of one of them when the other is displaced.

8. In a coin-controlled machine for selectively vending articles of different sale values from a line of stacks thereof, movable ejectors arranged for independent actuation at different stacks, wedge plates for actuation with the different said ejectors, a line of normally engaged members extending across and contacting in the paths of movement of the wedge plates, removable stop

elements normally engaged across the line of said members to cooperatively prevent a separation of the members by a wedge plate of any ejector and so prevent an operative actuation of the ejectors, 5 said stop elements being operative in the line of members for different distances of separation of the members which correspond to and vary inversely with the values of coins to be inserted in the machine by the purchaser of an article therefrom, and said wedge plates being of different 10 thicknesses corresponding to the different distances of separation permitted for the members

when the different stop elements are singly or collectively inoperative whereby only those ejectors may be thereafter actuated which have wedge plates of a thickness which is no greater than the distance of permitted separation of the members as provided by the inoperative disposal of one or more of the stop elements, and means utilizing a coin deposited in the machine to inoperatively dispose the stop element corresponding to the value of the coin.
